UNITED STATES PATENT OFFICE.

EDWARD A. LANGENBACH, OF CANTON, OHIO.

DESIGN FOR A CEILING-PLATE.

SPECIFICATION forming part of Design No. 26,239, dated November 3, 1896.

Application filed September 23, 1896. Serial No. 606,783. Term of patent 7 years.

To all whom it may concern:

- Be it known that I, EDWARD A. LANGENBACH, a citizen of the United States, and a resident of Canton, county of Stark, State of Ohio, have invented and produced a new and useful Design for Ceiling-Plates, of which the following is a full, clear, and exact description, reference being had to the accompanying drawings, making part of this specification.
- 10 The invention relates to a new design for a ceiling-plate; and it consists of a plate of the form and ornamentation shown in the accompanying drawings, in which—
- 15 Figure 1 is a plan view of the new design for a ceiling-plate, and Fig. 2 is a vertical sectional view of the same.
- 20 The leading feature of the design is a plate A, square in outline, having a raised marginal border 1, the extreme outer edge 2 of which is flat, and is provided with alternating ribs and circles 3 and 4, respectively, the outwardly

curved or bulged field 5, and the abruptly-bulged center 6. Surrounding the center is an ornamental ribbon-shaped figure 7, inclosed within a four-sided figure 8, the sides of which 25 are curved and appear to be connected by links 9. Adjacent to each of these curved sides is a fan-shaped figure 10, and between these figures and at the corners of the plate are the acorn-shaped figures 11 and leaves 12. 30 The border 1 is ornamented by the spirally-arranged scrolls 13 and at its corners by the figures 14.

What I claim is—

The design for a metallic ceiling-plate as 35 herein shown and described.

In testimony whereof I have hereunto set my hand this 30th day of July, A. D. 1896.

EDWARD A. LANGENBACH.
